Primary Examiner — Rhea Shields*(74) Attorney, Agent, or Firm* — Middleton Reutlinger**CLAIM**

The ornamental design for a base for a medical cart, as shown and described.

DESCRIPTION

FIG. 1 is a front perspective view of a base for a medical cart, showing our new design; and,

FIG. 2 is a rear perspective view thereof.

The broken line disclosure represents unclaimed portions of the base for a medical cart in which the design is embodied.
